JOHN C. CARPENTER, OF HOUSTON HEIGHTS, TEXAS.

CARBURETER-REGULATING MECHANISM.

1,076,268.

Specification of Letters Patent.

Patented Oct. 21, 1913.

Continuation of application Serial No. 489,982, filed April 15, 1909. This application filed October 12, 1912. Serial No. 725,357.

To all whom it may concern:

Be it known that I, JOHN C. CARPENTER, a citizen of the United States, residing at Houston Heights, in the county of Harris 5 and State of Texas, have invented certain new and useful Improvements in Carbureter-Regulating Mechanism, of which the following is a specification.

My invention relates to new and useful 10 improvements in carbureter regulating mechanism.

The object of the invention is to automatically regulate the air and fuel valve of a carbureter, according to the speed of the 15 engine and the load being carried thereby.

This device was included in my application for patent on carbureters, filed April 15, 1909, Serial Number 489,982, and which was declared abandoned March 4, 1912, this 20 application being filed as a continuation of that application.

With the above and other objects in view, the invention has particular relation to certain novel features of construction and operation, an example of which is given in this specification and illustrated in the accompanying drawing which shows a sectional side elevation of a carbureter with the regulating mechanism attached thereto.

Referring now more particularly to the drawing, the numeral 1 refers to the carbureting chamber having a fuel inlet 2 and an air inlet 3, the former of which is controlled by the needle valve 4 which is threaded 30 through the upper portion 5 of the carbureting chamber and whose lower free end projects into the fuel inlet, and the latter of which is controlled by the valve 6, which is pivoted in the air inlet and may be opened and closed by the manipulation of the arm 7.

The throttle 8 of the carbureter is controlled by the throttle valve 9 by the manipulation of the arm 10, carried by the stem of said valve, and regulates the quantity 45 of mixture delivered to the engine.

The needle valve 4 may be adjusted up and down by turning the same and the fuel inlet thus opened or closed. This valve may be turned by the manipulation of the 50 arm 11 carried thereby.

The throttle rod is indicated by the numeral 12 and one end thereof is pivoted to the arm 10. This rod is manually operated and the throttle valve thus opened and closed and the rod may be set in the ordinary

manner at any point of the throttle opening. Pivoted to the throttle rod is a floating lever 13. A link 14 connects the lever 13 to the free end of the arm 11.

A governing device 15, responsive to engine speed, has been provided which is secured to the machine frame by means of clamp 16. The governor stem 17 slides in the hollow stub shaft 18, which rotates in the bearing 18', carried by the clamp 16, 65 and is attached to the free end of the lever 13. The governing device is driven by the engine through the pulley 19, rigidly mounted on the shaft 18. The free end of the arm 7 is connected to the floating lever 70 13 by means of a link 20, one end of which is pivoted to said arm 7 and the other end of which is pivoted to the floating lever 13.

The governor stem moves in harmony with the changes in engine speed, while the 75 throttle rod is moved in harmony with changes in engine load. The floating lever being hingedly connected with the governor stem and throttle rod operates upon them alternatively as fulcrums and is, therefore, 80 responsive to changes in engine speed and load. The air and fuel valves, 6 and 4, are connected with the floating lever and operate also in response to changes in engine speed and load.

In operation, the throttle is opened by the throttle rod which operates the floating lever 13, which in turn operates on the governor stem 17 as a fulcrum, so as to open the fuel valve in greater proportion than 90 the throttle and the air valve in less proportion. This gives a richer mixture for starting. As soon as the engine takes up its cycle, the governor stem advances and operates the floating lever which operates 95 upon the throttle rod as a fulcrum, partially closes the fuel valve through the link 14 and further opens the air valve through the link 20, giving qualitative regulation of the mixture as the speed and load vary.

What I claim is:

1. In a device of the character described, the combination with a fuel inlet; an air inlet; a carbureting chamber connected with and receiving from said fuel and air inlets; an air valve for controlling said air inlet; a mixture throttling means; and a governing means, responsive to engine speed, adapted to operate said air valve; of a lever operatively connecting said throt-

tling means, governing means and air valve and responsive to said throttling means and governing means so that the said lever may be operated by said throttling means, operate upon said governing means as a fulcrum, and regulate the operation of said air valve, or may be operated by said governing means, operate upon said throttling means as a fulcrum, and 10 regulate the operation of said air valve.

2. In a device of the character described, the combination with a fuel inlet; an air inlet; a carbureting chamber connected with and receiving from said fuel and air 15 inlets; a fuel valve for controlling said fuel inlet; a mixture throttling means; and a governing means, responsive to engine speed, adapted to operate said fuel valve;

of a lever operatively connecting said throttling means, governing means and fuel 20 valve, and responsive to said throttling means and governing means so that the said lever may be operated by said throttling means, operate upon said governing means as a fulcrum, and regulate the operation of said 25 fuel valve, or may be operated by said governing means, operate upon said throttling means as a fulcrum, and regulate the operation of said fuel valve.

In testimony whereof I have signed my 30 name to this specification in the presence of two subscribing witnesses.

JOHN C. CARPENTER.
